FRANK CONRAD, OF PITTSBURGH, PENNSYLVANIA, ASSIGNOR TO WESTINGHOUSE ELECTRIC & MANUFACTURING COMPANY, A CORPORATION OF PENNSYLVANIA.

STARTING MECHANISM FOR AUTOMOBILES.

1,385,983.

Specification of Letters Patent.

Patented Aug. 2, 1921.

Application filed April 19, 1917. Serial No. 163,179.

To all whom it may concern:

Be it known that I, FRANK CONRAD, a citizen of the United States, and a resident of Pittsburgh, in the county of Allegheny 5 and State of Pennsylvania, have invented a new and useful Improvement in Starting Mechanisms for Automobiles, of which the following is a specification.

My invention relates to starting mechanisms for automobiles and it has particular relation to such mechanisms as embody dynamo-electric machines and means for controlling the engagement of gear wheels for operatively connecting the dynamo-electric machines to the shafts of internal-combustion engines.

The object of my invention is to provide a simple and automatic arrangement whereby an operative connection may be established between the armature of a dynamo-electric machine and an engine shaft by the reciprocation of parts of comparatively light weight while little or no torque is effective to rotate the armature.

It has been proposed to employ motors having displaced armatures which reciprocate to effect the meshing of coacting gear wheels but they possess certain disadvantages in that they require the use of complicated switching mechanisms for preventing the rotation of the armature until the gear wheels are placed in mesh. This arrangement is necessary because, in the displaced position of the armature, the torque is sufficiently high to rotate the armature at a comparatively high rate of speed before the gear wheels are completely meshed.

In the operation of motors having armatures of the character described above, the reciprocating parts are very heavy and the shock resulting from the engagement of the parts, in case the coacting gear teeth are not in register, may seriously damage the gear teeth. An excessively long commutator must be provided in order that the brushes may be in engagement with it throughout the path of movement of the armature.

Patent No. 1,246,057, issued Nov. 13, 1917, 50 the assignee of which is also the assignee of the present application, covers an arrangement comprising a series-wound electric motor and an electromagnet in series relation to the motor for actuating a pinion into and out of engagement with the fly-wheel gear.

A short-circuited winding is inductively related to the series field-magnet winding of the motor in order to automatically prevent the magnetic field of the motor from attaining its normal strength except after a predetermined period for the purpose of enabling the electromagnet to effect the meshing of the gear wheels before the normal torque is applied to the armature. This arrangement has proven successful in practice 60 but it possesses a disadvantage which does not obtain in the present invention. In the former arrangement, the short-circuited or damper winding occupies considerable space adjacent the field-magnet poles of the motor 70 which might, otherwise, be available for an increased number of turns of the field-magnet winding.

According to the present invention, I provide a non-inductive shunt path for the series field-magnet winding of the motor that is of high resistance relatively to the field-magnet winding. The pinion, which is actuated into and out of mesh with the fly-wheel gear, is connected to the core member of 80 the electromagnet by means of a rod that is slidably mounted within a tubular armature shaft. When the circuit of the motor is closed, a rush of current occurs and the value of the inductance of the series field- 85 magnet winding is sufficiently high to cause a large portion of the current to traverse the high-resistance shunt path. The field-magnet winding is, therefore, energized gradually and the meshing of the gear 90 wheels is effected before the armature is rotated at such speed that the meshing operation is rendered difficult.

The details of my invention will be described in connection with the accompanying drawing, in which Figure 1 is a side view, partially in elevation and partially in section, of a portion of an engine fly wheel having my invention associated therewith. Fig. 2 is a diagrammatic view of circuits 100 and apparatus embodying my invention.

Referring particularly to Fig. 1, an engine fly wheel 1, only a portion of which is shown, is provided with gear teeth 2. An electric motor 3 has a field-magnet frame 4 which may be secured to any suitable stationary part of a motor vehicle. The motor has field-magnet pole pieces 5, each of which is provided with a coil 6 of a series field-magnet winding.

The motor armature 8 has a shaft 9 that is provided with a longitudinally extending bore 10. A rod 11, which is mounted for slideable movement therein, is connected, at one end, to a pinion 12 by means of a collar member 13 and nuts 14. The pinion 12 is slideably mounted on a portion 15 of the armature shaft 9 that is square in cross-section. The position of the rod 11, relatively to the armature shaft 9, is controlled by an electromagnet 16 that is located in an extended portion 17 of the motor casing and is in axial alignment with the armature shaft 9. The electromagnet comprises a coil 18 that is in series with the series field-magnet winding 6 of the motor. The rod 11 is provided with an enlarged portion 19 which constitutes the movable core member of the electromagnet. A spring 20, which is interposed between the core member 19 and one end of the casing 17, tends to maintain the rod 11 in such position that the pinion 12 is disengaged from the gear teeth 2. The motor is provided with a terminal member 21 which is connected to the coil 18 of the electromagnet. The other terminal of the coil 18 is connected to the motor windings by a suitable conductor 22.

The electrical connections of the motor and the electromagnet are diagrammatically illustrated in Fig. 2. The motor circuit comprises the armature winding 23, the series field-magnet winding 6, a manually operable switch 24, a storage battery 25 and the magnet coil 18. One of the battery terminals and one of the motor terminals are grounded, a single-wire system being employed. A non-inductive resistor 26 is permanently connected between the terminals of the series field-magnet winding 6. The ohmic resistance of the resistor may be, for example, ten times that of the field-magnet winding.

To start the engine, the operator closes the switch 24 to complete the motor circuit. The coil 18 is immediately energized to actuate the core member 19, the rod 11, and the pinion 12 to the left, as viewed in Fig. 1, against the force of the spring 20. The series field-magnet winding 6 will also be energized but to a relatively small degree because the inductive character of the winding causes a considerable portion of the current to temporarily traverse the shunt path comprising the resistor 26. By reason of the high resistance of the shunt path, the current through the series field-magnet winding increases gradually and the torque of the motor increases to a corresponding degree.

The effect of diverting a large portion of the current traversing the motor circuit is to delay or modify the normal operation of the motor while the gear wheels are being meshed. The effect is, therefore, to materially limit the field flux of the motor when

the circuit is initially closed, so that a very slight torque, if any, is effective to rotate the pinion 12 while it is being meshed with the gear teeth 2. The normal torque of the motor is available, however, substantially 70 upon the complete meshing of the coaxial gear teeth. The fly wheel is thereupon rotated to crank the engine.

When the engine starts under its own power, the motor circuit may be opened at 75 the switch 24. The coil 18 is then deenergized and the spring 20, which has been compressed, will then return the core member 19, the rod 11 and the pinion 12 to their respective illustrated positions, with the pinion 80 disengaged from the fly wheel 1.

If the operator fails to open the motor circuit immediately after the engine starts, the motor will be driven at a rapidly increasing speed. The counter-electromotive force 85 of the motor is thereby increased and the current traversing its circuit is reduced to such value that the pull exerted by the coil 18 is less than the force of the spring 20, whereupon the rod 11 is shifted to its normal position and the pinion 12 is disengaged from the gear teeth 2. It is obvious, therefore, that no damage may be caused by failure to open the switch at the proper time.

Among other advantages possessed by a mechanism constructed in accordance with my invention, it may be noted that the reciprocating parts are light in weight and are not an essential part of a dynamo-electric machine. Because of this latter fact, it is not necessary to provide a commutator of abnormal length or to rearrange the motor casing and bearings. The mechanism operates automatically, upon the closing of a simple switch, to effect the meshing of the pinion 105 with the fly-wheel gear while little or no torque is effective to rotate the pinion and the normal torque is effective when the gear wheels are completely meshed.

The inductive character of the field-magnet winding causes a current of abnormal value to traverse the shunt resistor temporarily. The high resistance of the shunt path causes a gradual change in the relative values of currents traversing the parallel 115 circuits. During the operation of the motor to crank the engine, a comparatively small current traverses the shunt path and the loss in energy by reason of the shunt path is practically negligible. The shunt resistor 120 occupies little or no space that might be utilized for the coils of the series field-magnet winding.

While I have shown and described a non-inductive path in shunt relation to the field-magnet winding of the motor, it is understood that such modifications may be made as fall within the scope of the appended claims without departing from the spirit of my invention.

I claim as my invention:

1. In a starting mechanism, the combination with a pair of coaxing gear wheels, and means comprising an electromagnet for shifting one of said gear wheels into and out of mesh with the other, of an electric motor operatively connected to one of said gear wheels, means for substantially simultaneously controlling a circuit comprising 10 said motor and said electromagnet, said motor having a field-magnet winding, and a non-inductive path of relatively high resistance in permanent parallel relation to said field-magnet winding, whereby the energization of said field-magnet winding is delayed relatively to the operation of said electromagnet.
2. In a starting mechanism, the combination with a pair of coaxing gear wheels, 20 and means comprising an electromagnet for shifting one of said gear wheels into and out of mesh with the other, of an electric motor energized simultaneously with said electromagnet and operatively connected to one of 25 said gear wheels, said motor having a field-magnet winding, and a non-inductive resistor of relatively high value permanently in shunt relation to said field-magnet winding, whereby the energization of said field-magnet winding is delayed relatively to the operation of said electromagnet.
3. In a starting mechanism, the combination with a pair of coaxing gear wheels and an electric motor operatively connected to 35 one of said gear wheels, said motor having a field-magnet winding, of means comprising an electromagnet having a coil in series with said motor for actuating one of said gear wheels into and out of mesh with the other, and means for permanently providing 40 a path in shunt relation to said field-magnet winding whereby the ampere-turns of said winding are materially reduced tem-
- porarily upon the initial closing of the normal circuit of said motor.
4. In a starting mechanism, the combination with a pair of coaxing gear wheels and an electric motor operatively connected to one of said gear wheels, said motor having a field-magnet winding, of means comprising an electromagnet having a coil in series with said motor for actuating one of 50 said gear wheels into and out of mesh with the other, and means for permanently providing a path in shunt relation to said field-magnet winding, said path being of low inductance and high resistance relatively to said field-magnet winding.
5. In a starting mechanism, the combination with a pair of coaxing gear wheels and 60 means for shifting one of said gear wheels into, and out of, mesh with the other, of an electric motor operatively connected to one of said gear wheels, common means for controlling said shifting means and said motor, 65 said motor having a field-magnet winding and a non-inductive resistor of relatively high value permanently in shunt relation to said field-magnet winding, whereby the energization of said field-magnet winding is delayed relatively to the operation of said means.
6. In a starting mechanism, the combination with a shiftable gear wheel and shifting means therefor, of an electric motor for 75 rotating said gear wheel and having a field-magnet winding, common means for controlling said shifting means and said motor, and means permanently in shunt circuit relation to said winding for delaying its energization relatively to the operation of said shifting means.

In testimony whereof, I have hereunto subscribed my name this 3rd day of April, 1917.

FRANK CONRAD.
